LOOSE REED FOR LOOMS

Elbridge R. Holmes, Worcester, Mass., assignor
to Crompton & Knowles Loom Works, Worcester, Mass., a corporation of Massachusetts

Application December 9, 1930. Serial No. 501,095

2 Claims. (Cl. 139—189)

This invention relates to improvements in loose reeds for looms and it is the general object of the invention to provide an improved and simplified mechanism for easing the pressure of the reed at the time of beating up.

In the weaving of certain classes of goods it is desirable to permit the reed to have a limited freedom of motion with respect to the lay so as to accommodate itself to the picks as they are beaten into the cloth. During the backward stroke of the lay the reed must be rigid relatively to the lay to support the shuttle which is in flight at this time. It is a further object of my invention to provide relatively strong but resilient means for holding the reed substantially rigid with respect to the lay during the time that the latter is in the rear part of its motion, but to nullify the effect of this resilient device as the lay approaches beating-up position, so that the reed may be free to give a light beat to the filling if necessary. In order that there may be proper operation of the reed the latter is acted on permanently by light springs which can yield at the time of beat-up and which normally act in the same direction as the previously mentioned relatively strong resilient member so as to assist the latter in holding the reed fixed with respect to the lay at the time specified.

It is another object of my invention to employ the forward movement of the lay to act upon a part which in turn will overpower the relatively heavy resilient device referred to, the time of operation being variable to suit the desires of the user.

It is a still further object of my invention to provide a lever pivoted on the crank pin of the lay and acted upon by a fixed stop to arrest the action of the heavy resilient element as the lay moves forwardly, the lay itself being driven through the pivotal connection of the lever by so-called shock absorbing crank connectors.

It is another object of the invention to overpower the heavy resilient device by a force derived from the lay, thereby assisting in absorbing the energy of motion of the lay as the latter approaches front center. In this way the time may be increased during which a retarding force is exerted on the lay and the connector pin thereby spared some of the strain to which it is subjected when used without my invention.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a central vertical section through a loom taken transversely of the lay and showing my invention applied to one end of the lay with the latter in forward position and the reed loose,

Fig. 2 is a view similar to Fig. 1 but with the lay in rearward position and with the heavy resilient device operative to position the reed,

Fig. 3 is a detail rear elevation taken in the direction of arrow 3, Fig. 1, showing the parts on an enlarged scale,

Fig. 4 is a detail horizontal section on line 4—4 of Fig. 1, and

Fig. 5 is a horizontal section on line 5—5 of Fig. 3 but taken on an enlarged scale.

Referring to the drawings, I have shown a loom frame 10 having a crank shaft 11 with a crank arm 12 operably attached to a connector designated generally at 13. The latter comprises a pair of rods 14, each surrounded by a compression spring 15 which are stopped at their forward ends by means of nuts 16. The cross head 17 of the connector to which the rods 14 are attached has a forwardly extending arm 18 pivotally connected to the lay. The connector except for the particular way in which it is attached to the lay may be substantially the same as that shown in patent to Hillman No. 1,323,391 and of itself forms no part of my present invention.

The lay beam 20 is supported on swords 21, one of which is set forth in the drawings, each sword being mounted on a rocker pin 22 supported at the lower part of the loom frame. Each sword has at the upper end thereof a casting 23 provided with rearwardly extending ears 24 as shown in Figs. 3 and 4, said ears to be connected to the connectors in a manner to be set forth hereinafter. Associated with each lay sword 21 is a spring carrier 25 supported on the corresponding rocker pin and formed as shown particularly in Fig. 5 with a hook 26 to extend around the front part of the sword and having a rear arm 27 bent as at 28 to lie behind a large stiff spring 29. A screw 30 fastened through the bend 28 engages the spring 29 to vary the tension thereof. The lower end of the spring may be mounted as designated generally at 31. The upper end of the spring may be curved as at 32 and be positioned to engage the lower rail 33 of a reed structure

pivotedly mounted by means of pins 34 one of which is shown in Fig. 3. The pins are received by extensions 35 projecting upwardly from the lay. Comparatively light spring elements 36 may be operatively interposed between the rail 33 and

the lay beam 20. The lay beam 20 is supported on a lay sword 21 which is pivotally connected to a connector 13. The connector 13 is supported on a lay shaft 11 which is supported on a loom frame 10. The lay shaft 11 is supported on a lay sword 21 which is pivotally connected to a connector 13. The connector 13 is supported on a lay shaft 11 which is supported on a loom frame 10.

The lay beam 20 is supported on swords 21, one of which is set forth in the drawings, each sword being mounted on a rocker pin 22 supported at the lower part of the loom frame. Each sword has at the upper end thereof a casting 23 provided with rearwardly extending ears 24 as shown in Figs. 3 and 4, said ears to be connected to the connectors in a manner to be set forth hereinafter. Associated with each lay sword 21 is a spring carrier 25 supported on the corresponding rocker pin and formed as shown particularly in Fig. 5 with a hook 26 to extend around the front part of the sword and having a rear arm 27 bent as at 28 to lie behind a large stiff spring 29. A screw 30 fastened through the bend 28 engages the spring 29 to vary the tension thereof. The lower end of the spring may be mounted as designated generally at 31. The upper end of the spring may be curved as at 32 and be positioned to engage the lower rail 33 of a reed structure

the lay so as to permit a relative separation of these two parts under comparatively light pressure.

The matter thus far described is of common construction and has been employed for some time on certain types of looms, such as those weaving silk. The yielding devices designated generally at 36 have not always been associated with spring 29 but they or their equivalents have been employed to provide yielding means. In the prior practice it has been customary to have the upper end of the spring 29 bear directly against the rail 33 at all times, but it has been found desirable to alter this practice so as to permit a lighter beat of the reed against the filling.

In carrying my invention into effect I provide a construction wherein the spring 29 is over-powered as the lay reaches the forward part of its stroke by mechanism which is preferably though not necessarily mounted on the part which establishes pivotal connection between the connector 18 and the ears 24. Accordingly, I provide for each connector a pin or stud 40 which passes through the ears 24 and the forward end of the connector 18. Each connector and spring 29 may have associated therewith a structure about to be described and to facilitate an understanding of the invention I will describe but one of the mechanisms, although it is to be understood that each lay sword of the loom may be so equipped.

The stud 40 has a relatively large portion 41 which extends through one of the ears 24 as shown in Fig. 4, the left end of the stud being reduced as at 42 to pass through the other ear and being threaded to receive a nut 43. That part of the stud which extends beyond the threaded portion is still further reduced as at 44. The right and left hand ends of the stud have pivoted thereto, respectively, arms 45 and 46, said arms being connected together by a cross bar 47 and in effect forming with the latter a yoke. A leg 48 depending from the bar 47 is positioned for engagement with a stud 49 constituting a normally fixed but adjustable stop, said stop being held in adjusted front and back position by means of a nut 50 clamping it to a small stand 51 held in position by a bolt 52. The stand 51 has a horizontal slot 53 through which the stud 49 passes and it is by reason of the adjustment in the position of the stud afforded by the slot that the time of engagement between the leg 48 and the stud 49 may be varied.

There is extending laterally from the bar 47 a finger 54 which as shown in Fig. 3 extends inwardly toward the center of the loom and lies in front of the upper portion of the spring 29. An adjustable stop screw 55 passing through the bar 47 is positioned to engage the casting 23 and thereby limit forward movement of the bar and leg under action of the spring 29.

In operation, when the lay is in the position shown in Fig. 2 the leg 48 is under control of the spring 29 by reason of the fact that the latter bears against the finger 54 and holds the stop screw 55 against the casting 23. The screw 55 is capable of assuming several positions and is made adjustable to afford the user an opportunity to vary to some extent the pressure exerted by the upper end of the spring against the reed rail 33. If the screw 55 be moved forwardly its effect would be to move the finger 54 rearwardly with respect to the lay and thereby draw the spring away from the rail 33. When the parts are in the position shown in Fig. 2 the leg 48 is spaced from the stop stud 49.

As the lay continues to move forwardly the spring will maintain its contact with the rail 33 until the leg 48 engages the stud 49, at which time the yoke and leg, which in effect constitute a disabling lever, alter the character of their forward motion. The axis of this disabling lever, which is the connector pin for the lay, moves forwardly with the latter, but the lower end of the lever is of course held against further advance movement by the fixed pin 49 and the finger 54 therefore moves forwardly at a rate less than that at which the lay advances. In this way the upper end of the spring 29 is gradually moved away from the reed rail 33 and at the time of beat-up is sufficiently spaced from the latter so that the reed is free to respond to the conditions of beating-up and may move rearwardly with respect to the lay against the action of the light spring elements 36. As the lay starts to move rearwardly following its beat-up the upper end of the spring 29 will approach the rail 33 and will exert its full force against said rail when the leg 48 starts to move away from the stop 49.

The disabling of the spring 29 occurs at a time when the momentum of the lay is being dissipated, or at such times as the lay approaches its momentary stop at front center. The spring 29, being acted upon by the fixed stud 49 at this time, assists in absorbing the energy of movement of the lay and there is accordingly not so much wear on the pivot pin between the connector and the lay as would otherwise occur. The adjustability of the position of the stop 49 enables the user not only to vary the time for the release of spring pressure against the rail 33, but also permits a lengthening of the time during which the spring is effective to absorb the momentum of the lay as the latter approaches its foremost position.

With reference to Figs. 1 and 2 it will be seen that the disabling lever 48 is formed so as to be symmetrical about the plane passing through the axis of the stud 40 and the center of the finger 54, the purpose of this construction being to permit the same casting to be used on both the right and left hand sides of the loom.

From the foregoing it will be seen that I have provided a simple means for relieving the pressure on the reed at the time of lay beat-up whereby the motion of the lay is employed to remove the pressure of the relatively heavy spring 29. It will be noted that both the resilient means 29 and 36 are operatively related to the rail 33 when the lay is in rearward position, but that the heavier of these means is disabled during the latter part of the forward stroke of the lay so that the lighter means 36 only are responsible for the position of the reed with respect to the lay. Furthermore, it will be seen that the stop 49 may be varied as to position for the purpose of altering the point in the cycle of the loom at which the spring 29 is disabled. The spring 29 also acts through the fixed stop to assist in absorbing the momentum of the lay as the latter approaches front center, thereby distributing over an appreciable length of time the dissipation of the energy of the motion of the lay to spare the connector pins of the lay excess wear. It will also be seen that the pins which form the attaching means between the connector and the lay are so formed as to afford pivotal connection for the disabling lever. Furthermore, the shock absorbing crank connectors which yield to prevent excess strain of beating up are connected to the same pin which supports the disabling lever.

Having thus described my invention it will be seen that changes and modifications may be made therein by those skilled in the art without departing from the spirit and scope of the invention and I do not wish to be limited to the details herein disclosed, but what I claim is:

1. In a loom, a lay movable back and forth therein, a reed normally held in forward position but movable rearwardly with respect to the lay, a resilient member normally holding the reed in forward position relatively to the lay, a disabling lever pivoted to the lay and having a part to be operatively related to the resilient member, and a fixed stop to engage the disabling lever, the latter engaging said stop during forward movement of the lay and effective to move the resilient member out of controlling relation with respect to the reed during forward movement of the lay.

20

2. In a loom, a lay movable back and forth therein, a reed normally held in forward position but movable rearwardly with respect to the lay, a resilient member normally holding the reed in forward position relatively to the lay, a disabling lever pivoted to the lay and having a part to be operatively related to the resilient member, and a fixed stop to engage the disabling lever, the latter engaging said stop during forward movement of the lay and effective to move the resilient member out of controlling relation with respect to the reed during forward movement of the lay, the resilient member normally holding the lever fixed with respect to the lay when said lever is out of engagement with the fixed stop.
